UNITED STATES PATENT OFFICE.

EVALD JULIUS ENGMAN, OF SYRACUSE, NEW YORK, ASSIGNOR TO WILL & BAUMER CANDLE CO., INC., OF SYRACUSE, NEW YORK.

CANDLE LATHE.

Application filed July 26, 1922. Serial No. 577,742.

To all whom it may concern:

Be it known that I, EVALD JULIUS ENGMAN, of Syracuse, in the county of Onondaga, in the State of New York, have invented new and useful Improvements in Candle Lathes, of which the following, taken in connection with the accompanying drawings, is a full, clear, and exact description.

10 This invention relates to certain improvements in a candle lathe adapted to be used more particularly for turning or drilling the bases of candles to enable them to be conveniently supported in or upon special forms

15 of candelabra or other suitable supports. These candles are usually made in cylindrical form of considerable length with a central wick passing therethru, and are afterward cut transversely into desired 20 lengths; and the main object of my present invention is to provide a simple, practical and efficient lathe whereby one end forming the base of the candle may be conveniently and expeditiously turned or bored 25 to a predetermined diameter or taper according to the size or shape of the holder upon which the candles are to be mounted.

Owing to the delicacy and fragility of the material from which the candles are 30 usually made, the machine contemplates the feeding of the candle by hand into and out of engagement with the cutting tools of the lathe so as to avoid as far as possible mutilation of the surface of the candles; and another object of the invention is to provide 35 an adjustable stop for limiting the endwise movement of the candle in a direction necessary to produce the desired cut so that when once set, the length of the cut of all 40 candles inserted in the machine will be the same, the object of the adjustability of the stop being to permit the bases of the candles to be machined at different lengths.

A further object is to provide adjustable 45 means for centering and guiding the candles in their axial movement as they are moved by hand into and out of engagement with the cutting tool.

A still further object is to operate the 50 rotary cutting tool by means of a direct-connected motor preferably an electric motor mounted upon the same support as and coaxial with the bearing for said cutter.

Other objects and uses relating to specific

parts of the machine will be brought out in 55 the following description.

In the drawings:

Figure 1 is a top plan of a machine embodying various features of my invention as used for turning the bases of the candles 60 to a reduced diameter.

Figure 2 is a longitudinal vertical sectional view of the same machine taken on line 2—2 Figure 1.

Figures 3, 4 and 5 are enlarged transverse sectional views taken respectively in the plane of line 3—3 Figure 2, and on lines 4—4 and 5—5 Figure 1.

Figure 6 is a detail sectional view of a modified form of cutting head and cutters 70 thereon for tapering the bases of candles.

Figure 7 is a sectional view of the tubular candle guide similar to that shown in Figure 2 except enlarged.

Figure 8 is a transverse sectional view 75 taken in the plane of line 8—8 Figure 6.

Figure 9 is a detail sectional view partly in elevation of a further modified form of cutter for producing a tapering bore centrally in the base of the candle, and a modified form of adjustable stop for limiting the endwise movement of the candle into engagement with the cutter.

As illustrated in Figures 1 to 5 inclusive, this machine comprises a main supporting 85 frame or bed —1— disposed in a substantially horizontal position and provided on its upper side with lengthwise ways —2— for receiving and supporting a candle guide —3— and a candle rest —4— both of which 90 are adjustable along and upon the ways —2— and are held in their adjustable position by suitable clamps —5—.

An electric motor —6— and a journal bearing —7— are mounted upon the bed 95 —1— in coaxial relation with each other and with the guide —3—, the bearing —7— serving to receive and support a rotary tool holder —8—.

This tool holder is provided with a cylindrical shank —9— journaled in the bearing —7— and provided with a central lengthwise threaded aperture —10— for receiving an adjustable stop screw —11—, said shank —9— having one end coupled to the adjacent end of the armature shaft —12—, and its other end provided with a forked head —13—.

The free ends of the opposite arms of the head —13— are provided with guide openings —14— disposed in substantially the same radial plane at opposite sides of and at equal angles to the axis of the rotary tool holder —8— for receiving a pair of cutting tools —15— which are adjustable in the openings —14— toward and from the axis of the holder, and are held in their adjusted position by set screws —16—.

The head of the adjustable stop —11— is movable axially between the cutters —15— and base of the tool holder —8— so as to permit the distance between said cutters and head of the limiting stop to be adjusted at will for determining the length of the cut on the base of the candle as —a— as the latter is fed by hand thru the guide —3— and upon the rest —4— in the act of turning the base of the candle.

The guide —3— includes a tubular bushing —17— removably secured in its supporting bracket —18— by means of a thumb screw —19— so as to permit different bushings to be used according to the diameter of the candle, the base of which is to be turned, it being understood that the opening in the bushing through which the candle is moved is preferably of substantially the same diameter as that of the candle and serves as a means for centering the candle relatively to the axis of the rotary tool holder —8—, and also for holding the candle against lateral vibration during the turning operation.

The candles to be operated upon may vary materially in length, and the adjustability of the guide —3— and rest —4— permits the candles of different lengths to be properly supported against decentering or vibration during the turning operation on the base thereof without liability of marring the surface of the main body of the candle.

The candle rest —4— includes a head —20— having a lengthwise V-shaped groove in its upper side for receiving the adjacent portion of the candle, said head being provided with a threaded shank extending thru a vertical opening in the supporting base as —21— which is formed with a transverse slot —22— for receiving a nut —23— engaging the threaded shank of the head —20— for adjusting said head vertically to properly support the adjacent end of the candle —a— as the latter is moved back and forth in the guide —3—.

The head —20— is also provided with a pendant key or pen —24— entering a corresponding opening in the bracket —21— to prevent turning of said head or rather to keep the groove in the upper face thereof in alignment with the guide —3—.

The machine thus far described is for turning the base of the candle to a reduced diameter, but in some instances it is desired

to taper the base of the candle by turning, and for this purpose is provided a slightly modified form of forked head —8— and a pair of opposite longitudinally extending cutter blades —15'— which are secured to opposite faces of the opposite arms of said head by clamping bolts —16'—, the openings as —14'— in the blades for receiving said bolts being elongated transversely to allow the blades to be tilted to different angles relatively to the axis of the head to produce different tapers on the bases of the candles as shown more particularly in Figures 6 and 8.

In other instances, the bases of the candles are formed with central tapered bores for receiving corresponding supports, and in order that these bores may be formed expeditiously in such manner as to remove the adjacent portion of the wick without mutilating the candle, I have provided a further modified form of tool holder or rotary head —8''— shown in Figure 9 for receiving a tapered cutting tool —15''—, the free end of which is made in the form of a spiral cutter capable of cutting the wick in small pieces and allowing them to pass out with the other material as the tool enters the candle, the tool being secured in the holder by means of a set screw —16''—.

In this latter construction it is not practical to employ the center stop —11— by reason of the fact that the tool —15''— is centrally secured in the holder —8''—, and I have therefore substituted a modified form of stop —11'— consisting of a round rod —25— adjustably mounted in a lengthwise opening —26— in one side of the guide —3—, and adapted to be held in its adjusted position by a set screw —27— as shown in Figure —9—.

A stop plate —28— is secured to and projects radially from one end of the rod —25— between the guide —3— and tool holder —8''— to be moved into the path of the candle as —a— at one side of the tool —15''— for limiting the movement of the candle relatively to the tool so that the latter may enter the candle a predetermined distance only as determined by the position of the stop plate —28—.

In the operation of my invention, the motor —6— and parts driven thereby, are presumed to be in continuous action, and the cutters, stops and guides adjusted to operate upon a candle of certain size whereupon the candle blank is taken in hand and inserted endwise thru the guide —3— with the other end supported on the rest —4— at which time the candle is held by hand against rotation and advanced to the cutter until checked by the limiting stop engaging the end face thereof, thus completing the operation of turning or drilling the base of the candle after which the latter is withdrawn

by hand and the operation repeated with another candle.

By connecting the tool holder directly to the motor shaft, the cutting tools will be driven at a speed which, not only, greatly expedites the work of turning down or reducing the bases of the candles or drilling the tapered holes therein, but also reduces to a minimum the liability of mutilation of those portions of the candles, the turned or drilled surfaces being left in a smooth and satisfactory condition by reason of the high speed of rotation of the cutters.

In the use of the drilling tools shown in Figure 9, the peculiar spiral form of the free end of the cutter serves to sever the wick as well as to form a smooth bore in the candle stop and avoids any possibility of the wick becoming entangled with or wound upon the tool.

The devices are particularly simple and efficient for carrying out the objects of my invention, but it is obvious that various changes may be made in the detail construction without departing from the spirit of my invention.

What I claim is:

A candle lathe comprising a supporting bed having lengthwise guides on one end, a motor mounted on the other end of the bed with its shaft extending lengthwise of the guides, a journal bearing mounted on the bed between the guides and motor, a tubular shaft journaled in said bearing coaxial with and having one end secured to the motor shaft, a cutter secured to the other end of the tubular shaft to rotate therewith, a stop adjustable coaxially of and within the tubular shaft, separate brackets adjustable lengthwise of and upon the bed guides toward and from the cutter, a tubular candle guide in one of the brackets coaxial with the tubular shaft, and a candle rest mounted in the other bracket and adjustable radially of the produced axis of the tubular shaft.

In witness whereof I have hereunto set my hand this 21 day of July, 1922.

EVALD JULIUS ENGMAN.
